UNITED STATES PATENT OFFICE.

ROY C. MUNRO, OF CHICAGO, ILLINOIS, ASSIGNOR TO CHICAGO-CLEVELAND CAR ROOF-
ING COMPANY, OF CHICAGO, ILLINOIS, A CORPORATION OF ILLINOIS.

CARLINE CONSTRUCTION.

Application filed April 24, 1920. Serial No. 376,183.

To all whom it may concern:

Be it known that I, Roy C. MUNRO, a citizen of the United States, residing in Chicago, in the county of Cook and State of Illinois, have invented a new and useful Improvement in Carline Constructions, of which the following is a specification.

This invention relates to carline constructions, more particularly designed for use 10 in freight car roof frames, and has for an object the provision of a simple and economical construction by which the carline is strongly and firmly attached to the side frame members or side plates of the car 15 frame. The invention has for other objects such other improvements or advantages in construction and operation as are found to obtain in the structures and devices herein-after described or claimed.

20 In the accompanying drawings, forming a part of this specification, and showing, for purposes of exemplification a preferred form and manner in which the invention may be embodied and practiced, but without limiting the claimed invention to such 25 illustrative instance or instances:

Figure 1 is a vertical transverse section of a portion of a car roof frame provided with a carline construction embodying the 30 invention;

Fig. 2 is a plan view of the same;

Fig. 3 is an enlarged plan view of the construction employed at the point where the carline is attached to the side plate;

35 Fig. 4 is a section on the line 4—4 of Fig. 3;

Fig. 5 is a perspective view of one of the side brackets; and

Fig. 6 is a section on the line 6—6 of 40 Fig. 3.

The same characters of reference indicate the same parts throughout the several views.

Referring to the drawings, there is indicated at 11 the side plates of the roof frame, 45 these plates being suitably secured on the top of the side walls of a car and extending longitudinally along the opposite sides of the car.

The carline 12 consists of a single steel 50 bar, in the form of an angle bar, as shown in Fig. 6, having opposite stretches or reaches 13 and 14 which taper downwardly from the apex 15 of the carline to the ends 16, as shown in Fig. 1. The carline 12 may

support a wood filler 17 secured to the car- 55 line by a line of bolts and having oppositely tapered top edges 18 and 19. Formed in the apex of the filler 17 is a recess 20 in which is supported the usual ridge pole 21 of the car roof frame.

At its opposite ends, the carline 12 is supported by the side plates 11, and the construction by which said carline is so supported forms one of the principal features of the present invention. The construction at each side of the car and at each end of the carline is the same and accordingly a description of the construction at one end of the carline will suffice for both. Supported by the side plate 11 is a 60 side bracket 22, constructed in accordance with the invention, from a sheet metal blank formed to constitute a horizontal web 23 having at its outside edge a depending lip 24 and its inside edge a depending flange 25, from which is cut out and upwardly bent a supporting shelf 26. Preferably the shelf 26 is bent upwardly into a slightly inclined plane so as to lie substantially parallel with the horizontal leg 27 of the carline 12. The bracket 22 formed in the manner indicated is hung over the top of the side plate 11, as shown in Fig. 4, with the horizontal web 23 and the lip 24 respectively entering undercut portions cut in the top 65 and outside faces of the side plate 11. The inside flange 25 of the bracket 22 hugs the inside face of the side plate 11 and the bracket 22 may be firmly secured in place to the side plate by means of bolts 28 passed 70 through the side plate 11 and bolt holes 29 formed in the flange 25 of the bracket 22. When so secured the shelf 26 projects 75 upwardly from the side plate 11 for the support of the end of the carline 12. The bottom leg 27 of the carline rests on the shelf 26 and is secured thereto by means of rivets 30 passed through a line of rivet holes in the bottom leg of the carline and the shelf 26, whereas the vertical leg 31 of the carline 80 is secured to the inside flange 25 of the side bracket 22. For the latter purpose, there is provided an angle clip 32 one leg 33 of 85 which is riveted, as shown at 34, to the vertical leg 31 of the carline and the other leg 35 of which rests against and is riveted by one of the bolts 28 to the side flange 25 of the side bracket 22. By this construction

105

the carline is detachably though firmly secured to both the shelf 26 and the side flange 25 of the side bracket 22.

The invention as hereinabove set forth 5 is embodied in a particular form of construction, but may be variously embodied within the scope of the claims hereinafter made.

I claim:

1. A carline construction for freight car 10 roofs and the like, embodying side plates respectively extending along opposite sides of the car, brackets hung from and secured to said side plates, said brackets being constituted of sheet metal and respectively bent 15 to provide depending vertical flanges resting against the inner faces of the side plates, said vertical flanges being extended inwardly to form shelves, a carline having its horizontal portion secured at its ends to said 20 shelves, and angle plates separate from said bracket members connecting and securing the vertical portions at the ends of the carline to the vertical flanges of said brackets, substantially as specified.

2. A carline construction for freight car 25 roofs and the like, embodying side plates respectively extending along opposite sides of the car, bracket members of sheet metal hung from and secured to said side plates, each of said bracket members comprising a 30 horizontal flange adapted to engage the upper edge of the adjacent side plate and a depending flange adapted to engage the inner face of said side plate, the lower edge of said depending flange being divided into 35 two portions, one of said portions being adapted to be secured to said side plate and the other of said portions being bent upwardly to provide a substantially horizontal shelf portion, a carline of angle bar construction having its horizontal leg secured at its ends to said shelf portions of said bracket members, and angle plates separate from said bracket members connecting and securing the vertical leg at the ends of the 40 carline to the depending flanges of said bracket members, substantially as set forth.

ROY C. MUNRO.
